CRANKLESS PUMP

Walter Brauer, Ingelside, Tex.

Application May 3, 1946, Serial No. 667,160

9 Claims. (Cl. 103—166)

1
This invention relates to improvements in crankless pumps and refers more particularly to rotary pumps wherein a plurality of cylinders are equally spaced about a central pump head or stator.

Heretofore pumps of this type have been heavy compared to the capacity of the pump. One reason for this has been that the mounting of the rotor on the stator of necessity has been relatively large as the forces imposed on the rotor by the pistons or actuating rods has not been balanced but act principally in one direction at any given time. The amount and direction of the forces vary with the rotation of the rotor.

An object of this invention is to provide a rotary-type pump of relatively light weight compared to the capacity of the pump.

Another object is to provide a rotary-type pump having an even number of radially spaced cylinders wherein the stroke of the pistons in opposing cylinders are always in unison.

A further object is to provide a rotary-type pump wherein the major forces, to which the pump mechanism other than the rotor is subjected, are compressive and are balanced.

Still another object is to provide a rotary-type pump wherein the actuating rods have a rocking connection with the rotor.

A still further object is to provide a rotary pump having a roller bearing race assembly connection between the rotor and actuating rods in which the outer race is rotated whereby the power applied to the actuating rods on their compression strokes is relatively constant throughout the strokes.

Yet another object is to provide a rotary pump wherein opposite cylinders are in communication thus equalizing the pressure therein and insuring a balancing of opposing forces.

Other and further objects will be apparent from the following description:

In the accompanying drawings which are a part of the instant specification and are to be read in conjunction therewith and wherein like reference numerals are employed to indicate like parts in the various views:

Fig. 1 is a top plan view partially in section of a pump embodying this invention;

Figs. 2 and 3 are complementary vertical sectional views taken along the axis of the drive shaft of the pump shown in Fig. 1;

Fig. 4 is a fragmentary section of one of the bearing and race assemblies illustrating the assembly thereof;

2
Fig. 5 is an enlarged front elevation of the connector for securing the piston rod to the roller race;

Fig. 6 is an enlarged rear elevational view of the connector shown in Fig. 5.

Figure 7 is a transverse, vertical sectional view taken on the line 7—7 of Figure 1.

Broadly, the pump of this invention comprises a stator or central pump head having an even number of equally spaced radial cylinders with fluctuating members therein and rotor means for actuating members in opposing cylinders in unison whereby the stresses and forces encountered in operation are balanced.

15 Referring to the drawings, and more particularly Fig. 1, the pump is shown in top plan wherein the numeral 10 designates the upper casting plate and the stator or pump head 11 is mounted centrally thereof. An even number of cylinders 12 are spaced equally about the stator. The cylinders are arranged radially in such fashion that the axis of opposing cylinders are contained within the same vertical plane. However, the axis of opposing cylinders lie in two spaced apart horizontal planes. This arrangement of the cylinders in different horizontal levels facilitates actuation of the pistons 13 in opposing cylinders in unison as will be herein-after more fully explained.

20 30 The cylinders are secured to the stator by means of flanges 12a intermediate their ends and bolts 14. The inner ends of the cylinders abut tapered shoulders on bosses 11a on the stator. These beveled surfaces provide a seal therebetween.

35 The cylinders 12 communicate with valved inlet and outlet connections of the stator. The stator has a central passage 11b, one end of which may be connected to a source of fluid to be pumped. This fluid source, in the interest of simplicity, is not shown in the drawings. The end of the passage 11b not connected with the source of fluid may be closed by a suitable head or plug.

40 It is contemplated that both ends of the passage may communicate with the fluid source. The central passage 11b communicates with the cylinders through a plurality of ports 11c. A valve assembly is provided in these ports consisting of a combination seat and cage 15 in which the disc valve 16 operates. The valves are opened by surge of fluid on the suction stroke of pistons 13 and are seated by pressure on the compression stroke of the pistons. The bosses 11a which receive the cylinders serve as stops limiting upward movement of valves 16. Suitable openings in the 45 stator are closed by plugs 17. The openings are

provided to facilitate fabrication, assembly and repair of the stator.

Cylinders 12 communicate with an outlet connection 18 through ports 19 equipped with suitable disc valves 20 and seat rings 21. In the upper portion of the stator is an annular passage 11d forming a pressure chamber communicating with outlet connection 18 and through passages 19 with the cylinders. Openings are provided about the top of the stator to further facilitate fabrication, assembly, and repair of the stator. The openings are closed by plugs 22 which carry depending rods. The rods serve as stops limiting the upward movement of valves 20. Valves 20 are seated on the suction stroke of the pistons and are opened by surge of fluid on the compression stroke of the pistons.

In order to further equalize stresses in the opposing cylinders and the drive connections of their pistons, conduits 23 are provided between the opposing cylinder chambers to equalize the pressure therein. Thus the balance of the pump is not destroyed by leaky valves, packing or the like.

Pistons 13 are mounted on the ends of connecting rods 24. Split rings 25 are clamped over the free ends of the cylinders. These split rings have a central aperture which slidably receives the rods. Vents 25a are provided in the ring halves. The other ends of rods 24 have a driving connection with rotor 26 which will be hereinafter more fully explained.

A series of spokes or supports 27a radiate from the stator and position the lower casing 27. Casing 27 and upper casing plate 10 form a housing and oil sump for rotor 26 and the driving connections associated therewith. Windows or openings are provided in upper casing plate 10 facilitating access to the rotor. These openings are provided with removable cover plates 28.

The inner wall of plate 10 is provided with openings 10a and 10b which receive respectively bossed inserts 29a and 29b which may have suitable packing. These inserts slidably receive the connecting rods 24.

The mounting of rotor 26 is best shown in Figs. 2 and 3. The rotor carries three roller bearing races at different horizontal levels. The lower race 26a and a stationary race 30 mounted on casing 27 are concentric with the stator. Roller bearings 31 operate in the races and are mounted on spindles 32 carried by a spacer ring 33. These roller bearings are of special construction and the manner of assembly of the bearings in the races is illustrated in Fig. 4. The bearings have a doughnut shape. In assembly of the races, the bearings are aligned obliquely as shown in Fig. 4 relative to the races and when all are in position the races are brought into horizontal alignment with the bearings in proper position. Spacer ring 33 is then positioned with the spindles 32 serving as shafts as previously described. The spacer ring and spindles hold the races in horizontal alignment.

The other races 26b and 26c of the rotor are positioned eccentric with the stator and race 26a. The arrangement is such that the maximum throw of the races is disposed 180° relative to each other. The lower race 26b has a driving connection with pistons 13 operating in lower cylinders 12. The upper race 26c has operable connections between pistons 13 operable within the upper cylinders 12. As the opposing cylinders are positioned at different levels, rotation of the rotor serves to reciprocate the pistons within opposing cylinders in unison.

The drive connections between the rotor and connecting rods 24 are the same for each cylinder and to simplify their description, discussion of the drive connections will be confined to those for a single rod 24. The inner race 34c is also identical to the inner race 34b. The bearing assemblies with the doughnut type rollers 31 are assembled in the same fashion as described in connection with the races 26a and 30.

On the inner surface of race 34c are integrally formed hooks 35 as best shown in Fig. 1. Hooks 35 are adapted to fit over rollers 36 which are removably held in end recesses of connecting member 37, detailed in Figs. 5 and 6. This mounting is such that slight lateral movement of connector 37 is permitted relative to the race to accommodate the lateral displacement of the eccentric race in operation. The races 34b and 34c also have recess portions 38 on their inner surfaces intermediate hooks 35. These surfaces and the corresponding recesses in the back side of member 37 accommodate rollers or thrust bearings 39. Connector 37, at its front lower edge, has a projection 37b with an upturned dog at its extreme edge. This dog and a corresponding depending dog on plate 40 serve to position the adjacent end of rod 24 relative to connector 37. The adjacent surface of rod 24 is arcuate and fits in an arcuate recess in the front face of member 37, whereby a rocking or knuckle joint is provided. This mounting obviously permits some relative movement between the confronting surfaces. An arrangement such as this is required in order to have the ends of the connecting rods secured to the inner races.

In order to drive the rotor, a suitable gear 41 is provided which meshes with a pinion 42. The pinion is carried by a shaft 43 actuated by a suitable prime mover not shown in the drawings.

Shaft 43 is journaled in the pump housing and a suitable stuffing box 44 is provided to prevent loss of lubricant from the sump.

Lubrication of the various roller assemblies and other moving parts is required and readily accomplished by means of a lubricant circulating system comprising a pipe 45 communicating with a low portion of the sump or housing such as is provided to accommodate the pinion 42. A suitable pump 46 may be provided with its plunger actuated by race 34b. Lubricant distributor lines 47 and 48 shown respectively in Figs. 3 and 2 supply lubricant to the various working parts. The lubricant drains to the bottom of the housing and continuous circulation in a fashion well known to those well skilled in the art is obtained.

In operation, passage 11b of the stator is connected to a suitable source of fluid to be pumped and the outlet is suitably connected by a pipe 18 to the destination for the fluid. The rotor is actuated by the prime mover through a suitable gear arrangement such as 41 and 42. The principal stresses on the connecting rods and stator are compressive and in a radial direction. The rotor is of relatively heavy construction and easily withstands these stresses as the arrangement is such that the stresses are balanced circumferentially of the rotor.

The eccentricities of the rotor on revolution serve to reciprocate the pistons in the cylinders producing alternate suction and compression strokes. On the suction strokes of the pistons fluid is drawn through ports 11c into the pump chamber and cylinder. Valves 16 are unseated by the pressure differential across the valve seat. On the compression strokes the piston forces the fluid

within the pump chambers and cylinders past valves 20, which are unseated by the pressure differential across seat 21. All the cylinders communicate with a single pressure chamber or annular space 11d which in turn communicates with the outlet and pipe 18.

The connections between the piston rods and inner races 34b and 34c are such that lateral movement of connectors 37 relative to the races is permitted. This rocking or knuckle connection insures true axial movement of connecting rods 24, the lateral movement of the eccentrics being compensated for by the connectors 37. As the outer races 26b and 26c of the rotor revolve about the inner races a wedge effect is provided through the rollers 31 whereby the power transmitted to the pistons is greatly increased, as compared with the regular crank type pump. The magnitude of the power is relatively constant throughout the stroke.

Lubrication of the moving parts is effected by means of pump 46, the plunger of which bears against the inner surface of race 44b and is reciprocated thereby to force lubricant through the lubricant distribution system comprising pipes 47 and 48.

The construction of the rotary pump is such that an individual cylinder may be separately dismantled for repairs or replacement of parts without the necessity of dismantling the entire pump. By the provision of cover plates 28 for the windows in upper casing plate 10, the connections between an individual connecting rod 24 and the rotor are readily accessible for purposes of repair or the like. The novel rollers 31, of doughnut shape, with the spacer rings 33 and spindles 32 are readily assembled between the rigid complete or integral ring races 26a and 38, as well as the races of the eccentrics. The piston driving bearing races 26b and 26c may be machined in the rotor.

In order to insure the balancing of the stresses in the pump in operation, even though a valve or packing may become faulty and leak, the pump chambers of opposing cylinders are inter-connected by conduits whereby the pressure within opposing cylinders is always equal. Thus, in operation, excessive stress is never placed upon one side only of the rotor. The stresses caused by pump pressure are confined to the drive gear ring or rotor, radiate from the stator and are always balanced on opposite sides of the ring. This balancing of stresses makes possible the utilization of increased pump capacity per unit of pump weight. For this reason, the pump of this invention may be advantageously used as a portable unit mounted on a truck or other means of transportation. The mobility of this type unit lends itself readily to employment of the pump in field work as for instance in cementing operations in the oil fields, circulation of drilling mud in well bores, acidation of wells and the like. Obviously it is contemplated that pumps of this character may have a stationary mounting.

It will be seen that the objects of this invention have been accomplished. There has been provided a rotary type pump capable of increased capacity per unit weight of the pump. The arrangement of the pump is such that the stresses encountered in pumping operations are balanced at all times. The construction is such that the individual cylinders, pistons and driving connections are readily accessible for repairs without the necessity of dismantling the pump as a whole.

From the foregoing it will be seen that this invention is one well adapted to attain all of the

ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described my invention, I claim:

1. A crankless rotary pump comprising a stator having inlet and outlet connections, an even number of radial cylinders equally spaced about the stator, said cylinders having valved communication with the inlet and outlet connections, members mounted for reciprocation in the cylinders, a drive rotor mounted for rotation about the stator and cylinders, and connections between the rotor and members operable to actuate the members of opposing cylinders in unison and in the same pumping sense on actuation of the rotor.

2. A crankless rotary pump comprising a stator having inlet and outlet connections, an even number of radial cylinders equally spaced about the stator, said cylinders having valved communication with the inlet and outlet connections, pistons reciprocally mounted in the cylinders, a drive rotor mounted for rotation about the stator and cylinders, and connections between the rotor and pistons operable to reciprocate the pistons of opposing cylinders in unison and in the same pumping sense on actuation of the rotor.

3. A crankless rotary pump comprising a stator having inlet and outlet connects, an even number of radial cylinders equally spaced about the stator, said cylinders having valved communication with the inlet and outlet connections, unrestricted conduits between the pump portions of opposing cylinders, pistons reciprocably mounted in the cylinders, a drive rotor mounted for rotation about the stator and cylinders, and connections between the rotor and pistons operable to reciprocate the pistons of opposing cylinders in unison and in the same pumping sense on actuation of the rotor.

4. A crankless rotary pump comprising a stator having an inlet chamber and a pressure chamber, an even number of radial cylinders equally spaced about the stator, said cylinders having valved communication with the chambers, pistons reciprocably mounted in the cylinders, a drive rotor mounted for rotation about the stator and cylinders, and connections between the rotor and pistons operable to reciprocate the pistons of opposing cylinders in unison and in the same pumping sense on actuation of the rotor.

5. A crankless rotary pump comprising a stator having inlet and outlet connections, an even number of radial cylinders equally spaced about the stator in two parallel planes, said cylinders having valved communication with the inlet and outlet connections, opposing cylinders positioned in different parallel planes, pistons reciprocably mounted in the cylinders, a drive rotor mounted for rotation about the stator and cylinders, and connections between the rotor and pistons operable to reciprocate the pistons of

opposing cylinders in unison and in the same pumping sense on actuation of the rotor.

6. A crankless rotary pump comprising a stator having inlet and outlet connections, an even number of radial cylinders equally spaced about the stator in two parallel planes, said cylinders having valved communication with the inlet and outlet connections, opposing cylinders positioned in different planes and having their pump portions communicating with one another, pistons reciprocably mounted in the cylinders, a drive rotor mounted for rotation about the stator and cylinders, and connections between the rotor and pistons operable to reciprocate the pistons of opposing cylinders in unison and in the same pumping sense on actuation of the rotor.

7. A crankless rotary pump comprising a stator having inlet and outlet connections, an even number of radial cylinders equally spaced about the stator, said cylinders having valved communication with the inlet and outlet connections, said cylinders positioned in two spaced parallel planes with opposing cylinders in different planes, pistons reciprocably mounted in the cylinders, a drive rotor mounted for rotation about the stator and cylinders, two eccentrics carried by the rotor at levels corresponding to the cylinder levels, the throw of said eccentrics disposed 180° relative to each other, and drive connections between the pistons of cylinders of each level with the eccentrics of corresponding levels.

8. In a crankless rotary pump, a central stator having inlet and outlet connections and provided with an even number of cylinders radially disposed therein in two spaced planes normal to the axis of the stator, said pistons having valved communication with the inlet and outlet connections, opposing cylinders being disposed in different planes, a rotor concentric with the stator and rotatably mounted, two eccentric roller bearings and inner and outer race assemblies carried by the rotor and disposed 180° relative to each other, said assemblies lying in the planes of the cylinders, respectively, members mounted for reciprocation within the cylinders and connected to the assemblies residing in the

corresponding planes, each of said connections including a rod connected to one reciprocating member and having a knuckle-like connection with a connector at its opposite end, the inner race having a connection with the connector providing for slight movement therebetween along an arc concentric with the stator, and roller thrust bearings between the connector and inner race.

10 9. In a crankless rotary pump having a central stator provided with inlet and outlet connections and with radially disposed cylinders, said cylinders having valved communication with the inlet and outlet communications reciprocating members therein, and a rotor concentrically mounted thereabout and carrying a roller bearing and race assembly, the improvement which resides in the combination therewith of drive connections between the reciprocating members and race assembly each connection including a rod connected to one reciprocating member and having a knuckle-like connection with a connector at its opposite end, the inner race having a connection with the connector providing for slight movement therebetween along an arc concentric with the stator, and roller thrust bearings between the connector and inner race.
